ALARM SYSTEM

William N. Garwick, Kankakee, Ill.
(1135 Cornelia St., Pomona, Calif.)
Filed June 12, 1959, Ser. No. 819,986
5 Claims. (Cl. 340—227)

The present invention relates to an electrical fire and burglar alarm system for installation in a residential or commercial establishment.

Alarm systems presently in use in residential or commercial establishments are generally of the one circuit type employing the lighting system circuit. Frequently such an alarm system is rendered inoperative due to interruption of the lighting system circuit either by damage from fire or by unauthorized and deliberate cutting of the input portion of the circuit. Other systems presently in use or proposed have employed storage batteries for the source of electrical current. Such systems dependent upon storage batteries frequently fail to operate when desired due to the storage batteries losing their electrical charge.

An object of the present invention is to provide an alarm system which employs the electrical lighting system circuit as the primary source of electrical energy but has standby batteries in case the lighting system circuit fails for any reason.

Another object of the present invention is to provide an alarm system which incorporates features of a fire alarm system with a burglar alarm system.

A further object of the present invention is to provide an alarm system which is automatic in operation, one having a minimum of components, one requiring minimal inspection and maintenance, and one which is economically feasible.

These and other objects and advantages of the present invention will be fully apparent from the following description when taken in conjunction with the annexed drawings, in which:

FIGURE 1 is a plan view of a building showing the system of the present invention installed therein;

FIGURE 2 is a plan view of the furnace room of such a building as is shown in FIGURE 1, showing a portion of the alarm system of the present invention installed therein;

FIGURE 3 is a view on an enlarged scale, taken on the line 3—3 of FIGURE 2;

FIGURE 4 is a view partially in section of a portion of the assembly shown in FIGURE 3, as viewed from the opposite side;

FIGURE 5 is a bottom plan view of the assembly shown in FIGURES 3 and 4, as shown on line 5—5 of FIGURE 3;

FIGURE 6 is a view partially in section of a remote switch actuating means employed in a modified form of the invention;

FIGURE 7 is a plan view of the assembly shown in FIGURE 6;

FIGURE 8 is a schematic view of the electrical circuit employed in the alarm system of the present invention;

FIGURE 9 is a fragmentary elevational view showing a portion of the system secured to a window of a building; and

FIGURE 10 is a partial elevational view showing a portion of the system secured to a door of a building.

Referring in greater detail to the drawings in which like numerals indicate like parts throughout the several views, in FIGURE 1 the reference numeral 20 designates generally the exterior wall of a residential building having a kitchen area 22 and a living room area 24. In FIGURE 2, the wall 20 encloses a basement area 26 in which there

2

is a fuel supply tank 28, a work bench area 30, a furnace 32 and a hot water tank 34. The reference numeral 36 designates generally a fuse box in the house lighting circuit and dotted lines, as at 38, suggest the possible locations of a washing machine and dryer connected to the power lines which begin at the fuse box 36.

On another portion of the wall 20 is a gas meter 40 to which is connected the various gas appliances installed within the residence defined by the wall 20.

10 In FIGURE 1, the dotted lines at 42 designate a television or radio receiver within the living room area 24, the dotted lines 44 and 46 in the kitchen area 22 designate generally a refrigerator and a stove, respectively.

One of the actuating components is shown in the living room area 24 and designated by the reference numeral 48 and another component is shown in the kitchen area 22 and designated by the reference numeral 50.

15 A master unit of the system of the present invention is shown in FIGURE 2 and designated by the reference numeral 52. In connection with each of the components 48 and 50 and the master unit 52, the numerals 54, 56, 58, 60, 62, and 64 represent lengths of fusible plastic cord constituting heat fusible elements employed in the alarm system of the present invention.

20 Referring to FIGURE 8, a schematic view of the circuit employed in the alarm system of the present invention is shown with one of the actuator or actuating components 48, 50, shown in circuit with unit 52, it being understood that more than one component 48 or 50 may be employed with the unit 52, if found practical.

25 In FIGURES 3, 4, and 5, the unit 52 is shown in detail while in FIGURES 6 and 7 the components 48 and 50 are shown, it being understood that the components 48 and 50 are identical and will be described with reference to the component 48.

30 In the alarm system of the present invention there is a first circuit 66, and a second circuit 68. The first circuit 66 includes a pair of wires 70 leading to a source of electrical current, such as 110-volt residential lighting system circuit. The first circuit 66 includes a first normally open switch 72 and an electrical signal such as a bell or buzzer 74. As shown in FIGURE 8, the switch 72 includes fixed contacts 76 and 78 and a movable contact 80. The movable contact 80 is in circuit with the contact 78, a neon glow lamp 82, resistor 84, and the wires 70. The master switch 86 is in circuit with the movable contact 80 and fixed contact 78, lamp 82, and resistor 84 and when the switch 86 is closed and the circuit of the wires 70 is energized, the neon glow lamp 82 will be energized and illuminated.

35 The second circuit 68 includes a source of electrical energy, such as a storage battery 88, a normally open switch 90 having a fixed contact 92, a second fixed contact 94, and a movable contact 96.

40 The present invention provides a third normally closed switch 98 having fixed contacts 100 and 102 and a movable contact 104. The switch 98 connects the first circuit 66 to the second circuit 68. The movable contact 104 is normally in electrical contact with the one fixed contact 100. A step-down transformer 106 has its primary in circuit with the pair of wires 70 through the movable contact 80 and the fixed contact 76. The transformer 106 is normally not energized.

45 One terminal of the secondary of transformer 106 is connected to one of the fixed contacts 102 of switch 98. A signal lamp 108 is connected across said secondary. A buzzer 74 is connected across said secondary through the pole 104 of said switch 98 and said fixed contact 102. Said pole normally engages its other fixed contact 100. Connected across the secondary of said transformer is an

electromagnet 110, which when energized, shifts the pole 104 from fixed contact 100 to fixed contact 102.

In FIGURE 8, the reference numeral 112 indicates, in dotted lines, a length of fusible plastic cord, constituting a heat fusible element, one end of the cord being fixedly secured to a fixed object and the other end operatively connected to a tension spring 114. The cord 112 is shown operatively connected to the movable contacts 80 and 96 of the switches 72 and 90, respectively. A midportion of the cord 112 is supported upon a pulley 116. Upon severing of the portion of the cord 112 between the switch 72 and the fixed one end, the spring 114 serves to shift the contacts 80 and 96 from the contacts 78 and 94 to the contacts 76 and 92, respectively.

It is to be understood that the cord 112 is a schematic representation only and may be any one of the cord lengths 58, 60, 62, or 64, as shown in FIGURE 2.

Referring to FIGURES 3, 4, and 5, the unit 52 is shown in detail. It includes a base element 118 on which is mounted a U-shaped bracket 120 provided with a plurality of aligned holes, as at 122 in FIGURE 4. Mounted in each pair of aligned holes 122 in the bracket 120 is a plunger 124, here shown as five in number, although more or fewer may be employed as the circumstances warrant.

In FIGURE 4, the endmost one of the plungers 124 is shown to have the free end portion of the cord length 64 attached thereto, it being understood that the other cord lengths 58, 60, and 62 are attached to the other plungers 124. As the actions of all of the plungers 124 are identical, they will be described with reference to the plunger 124 having the cord length 64 attached thereto.

The plunger 124 has a head 126 on the end remote from the attaching means for the cord length 64 and a spring 128 is interposed between the head 126 and the adjacent leg of the bracket 120. The spring 128 is represented in the schematic view, FIGURE 8, by the spring 114.

Facing the heads 126 and the plungers 124 is a bar 130 carried on one end of a solenoid core 132. The core 132 is mounted for sliding movement within the solenoid coil 134 and has its end remote from the bar 130 secured to a non-metallic element or non-magnetic element 136 which has a portion adjacent one end projecting out of the coil 134.

A trip lever 138 is pivotally mounted upon a screw 140 secured in the base 118 and has one end provided with an upstanding leg 142 in the path of movement of the element 136.

The lever 138 carries a post 144 which bears against the free end of an actuating arm 146 of the microswitch 72, shown schematically in FIGURE 8. The other microswitch 90, also shown schematically in FIGURE 8, is shown in FIGURES 3 and 4 to be mounted on the switch 72 with its actuating arm 148 provided with an extension 150 which overlies and abuts a midportion of the arm 146 of the switch 72. The electrical connections of the switches 72 and 90 to the other components of the unit 52 are not illustrated for reasons of simplicity.

The switch 98, mentioned in connection with FIGURE 8, is also mounted on the base 118. The actuating arm 152 of the switch 98 is pivotally connected to the plunger 154 of the electromagnet 110.

The battery 88 and the transformer 106 are also mounted on the base element 118, as shown in FIGURE 3, and the neon glow lamp 82 is mounted in a suitable socket 156, shown in dotted lines in FIGURE 3, suitably supported on the base element 118. The lamp 108 is similarly mounted adjacent the glow lamp 82. A test light 158 and push button switch 160 are also mounted on the base element 118 and are shown, in FIGURE 8, to be in circuit with the battery 88 and a main switch 162, the latter also being mounted on the base element 118, as shown in FIGURE 3.

Referring to FIGURES 6 and 7, it will be seen that the component 48 is similarly provided with a sliding plunger

164 having one end connected to the fusible element or cord length 54. A spring 166 is circumscribed about the portion of the plunger 164 adjacent the other end and biases the plunger 164 for movement in a direction in which it will carry a bar 168 into contact with the operating button 170 of another microswitch 172.

The switch 172 is illustrated schematically in FIGURE 8. A switch 174 is in circuit with the switch 172 and is mounted in a place accessible to an occupant of the building. A main switch 86, in the lighting circuit, is mounted on the base element 118 adjacent the other main switch 162.

It is to be understood that the component 50, shown mounted in the kitchen area 22 in FIGURE 1, is identical in all respects with the component 48, above described.

For each cord length 54 or 56 with the component 48 and 50, it is understood that there is a separate operating plunger 164.

In FIGURES 9 and 10, the reference numeral 176 represents a cord length extending between one of the components 48 or 50 and either the window sash 178 or an edge portion of a door 180, the opening of either one of which will sever the cord length 176 and effect the actuation of the microswitch 172 in the component 48 or the component 50, as the case may be.

In operation, the switch components 48 and 50 are installed in suitable locations so that the fusible element may extend over the most probable sources of excessive heat such as the TV or radio 42 in the living room area 24 or over the refrigerator 44 and stove 46 in the kitchen area 22. Likewise, the unit 52 is established in a location and securely fixed to a proper support so that the cord lengths 58, 60, 62, and 64, and as many other cord lengths as may be found practical may extend over the most probable causes of excessive heat in the basement, FIGURE 2.

Upon tripping or melting of the cord lengths of the components 48 or 50, the associated microswitch 172 is energized. The switch 172 is connected in circuit with the solenoid coil 134 and when the latter is energized, the core 132 shifts the lever 138 to the position in which the post 144 moves out of engagement with the free end of the arm 146, permitting the springs within the switches 72 and 90 to shift their movable contacts 80 and 96 from engagement with the contacts 78 and 94 (FIGURE 8), to contacting engagement with the other fixed contacts 76 and 92, respectively.

The neon glow lamp 82 is normally illuminated, showing that the circuit of the lighting system is intact as far as the alarm system of the present invention is concerned.

Upon closing of the contact 80 with the contact 76, the transformer 106 is energized and the relay electromagnet 110 is energized to draw the movable contact 104 from the contact 100 into contact with the contact 102. This illuminates the lamp 108 and effects the sounding of the signal or buzzer 74.

If the lighting system circuit is disturbed in any way so that the transformer 106 cannot be energized, the electromagnet 110 will not be energized and the switch 98 will stay in the position shown in FIGURE 8. This connects the battery 88 to the buzzer 74 through the contact 92 and movable contact 96, after the associated fusible element has been broken and the associated plunger 164 is permitted to press inwardly the core 132 of the solenoid coil 134 and effect the shifting of the post 144 in the same manner as occurs when the solenoid coil 134 is energized as heretofore described.

It will be seen, therefore, that upon resetting of the lever 138 to the position in which the post 144 bears against the microswitch arms 146 and 148, the system is returned to normal and if current is present in the wires 70, the neon glow lamp 82 will be energized to signal that the system is in ready condition.

The only attention necessary to give the system after resetting it is an occasional test of the condition of the battery 88 by pressing of the pushbutton switch 160 and

observing the relative strength of the battery 88 by the degree of illumination of the light 153.

Another test that may be made in order to ensure the system is in working condition is to manually operate the core 132 of the solenoid coil 134, pressing the latter so as to disengage the arms 146 and 148 from the post 144 and effect the energization of the contacts 76 and 92 in the switches 72 and 90 to set into operation the buzzer 74 either by the current from the wires 70 or from the battery 88 in case there is no current in the wires 70.

What is claimed is:

1. In an alarm system, a first circuit including a first source of electrical current, a first normally open switch, an electrical signal device, and means to energize said signal device from said first source responsive to closure of said switch, a second circuit including a second source of electrical current, a second normally open switch, and a third normally closed switch, said second source, second normally open switch, and third normally closed switch being connected in circuit with said signal device, means urging said first and second switches toward closed position, a common severable, heat fusible element operatively connected to said first and second switches for holding both of the latter in open position, relay means controlling said third switch and opening same when energized, and circuit means connecting said relay means to said first source through said first switch, whereby to open said third switch responsive to closure of said first switch.

2. In an alarm system, a first circuit including a first source of electrical current, a first normally open switch, a nelectrical signal device, and means to energize said signal device from said first source responsive to closure of said switch, a second circuit including a second source of electrical current, a second normally open switch, and a third normally closed switch, said second source, second normally open switch, and third normally closed switch being connected in circuit with said signal device, spring means urging said first and second switches toward closed position, a common severable heat fusible element operatively connected to said first and second switches for holding both of the latter in open position, relay means controlling said third switch and opening same when energized, circuit means connecting said relay means to said first source through said first switch, whereby to open said third switch responsive to closure of said first switch, and manually actuatable means operatively connected to said first and second switches for actuating both of the latter at times to closed positions independently of said spring means.

3. In an alarm system, a first circuit including a first source of electrical current, a first normally open switch, an electrical signal device, and means to energize said signal device from said first source responsive to closure of said switch, a second circuit including a second source of electrical current, a second normally open switch, and a third normally closed switch, said second source, second normally open switch, and third normally closed switch being connected in circuit with said signal device, spring means urging said first and second switches toward

closed position, a common severable, heat fusible element operatively connected to said first and second switches for holding both of the latter in open position, relay means controlling said third switch and opening same when energized, circuit means connecting said relay means to said first source through said first switch, whereby to open said third switch responsive to closure of said first switch, and a solenoid operatively coupled to said first and second switches for actuating both of the latter to closed positions independently of said spring means.

4. In an alarm system, a first circuit including a first source of electrical current, a first normally open switch, an electrical signal device, and means to energize said signal device from said first source responsive to closure of said switch, a second circuit including a second source of electrical current, a second normally open switch, and a third normally closed switch, said second source, second normally open switch, and third normally closed switch being connected in circuit with said signal device, means urging said first and second switches toward closed position, a common severable heat fusible element comprising a length of fusible plastic cord having one end operatively connected to said first and second switches and having its other end connected to a fixed object for holding both of the first and second switches in open positions, relay means controlling said third switch and opening same when energized, and circuit means connecting said relay means to said first source through said first switch, whereby to open said third switch responsive to closure of said first switch.

5. In an alarm system, a first circuit including a first source of electrical current, a first normally open switch, an electrical signal device, and means to energize said signal device from said first source responsive to closure of said switch, a second circuit including a second source of electrical current, a second normally open switch, and a third normally closed switch, said second source, second normally open switch, and third normally closed switch being connected in circuit with said signal device, spring means urging said first and second switches toward closed position, a common severable, heat fusible element comprising a length of fusible plastic cord having one end operatively connected to said first and second switches and having its other end connected to a fixed object for holding both of the first and second switches in open positions, relay means controlling said third switch and opening same when energized, circuit means connecting said relay means to said first source through said first switch, whereby to open said third switch responsive to closure of said first switch, and manually actuatable means operatively connected to said first and second switches for actuating both of the latter at times to closed positions independently of said spring means.
